LOUIS C. STUKENBORG, OF MEMPHIS, TENNESSEE, ASSIGNOR TO OILDRAULIC LIFT COMPANY, OF MEMPHIS, TENNESSEE, A CORPORATION OF DELAWARE

LIFTING JACK

Application filed July 8, 1927. Serial No. 204,327.

My invention relates to lifting jacks and more particularly to a hydraulic or fluid pressure jack.

An object of the invention is to provide a lifting jack which requires but a minimum of pressure to lift and support a maximum load.

Further the invention provides a hydraulic jack wherein fluid is normally contained in an elevating piston which is conducted therefrom and discharged under pressure beneath the piston to elevate the latter, the fluid being conducted back into the hollow piston by the pressure thereof against the fluid head as the piston descends to normal position.

The invention also contemplates a lifting head designed to lift and support wheeled vehicles.

Still another object resides in the provision of a hydraulic or fluid pressure jack having means for automatically stopping the ascent of the piston when the latter reaches a predetermined point, thus obviating the danger of the piston moving from its cylinder.

With the preceding and other objects and advantages in mind, my invention consists in the combination, construction and arrangement of parts and objects to be hereinafter specifically referred to, claimed and illustrated in the accompanying drawing, wherein,

Figure 1 is a fragmentary top plan view of a hydraulic jack constructed in accordance with my invention, and

Figure 2 is a vertical sectional view of the same.

Referring to the invention a vertical cylinder 5 is provided having a removable bottom cap 6 and equipped with a stuffing box 7 at its upper end. Reciprocable in the cylinder 5 is a hollow piston 8 having a lower closed wall 9 and which is slidable through the stuffing box, and a packing gland 10 secured to the upper end of the stuffing box.

A lifting head is provided for raising and supporting motor vehicles and comprises a central rectangular body 11 having a central opening 12 in its under face into which the upper end of the hollow piston projects so that the body 11 rests directly upon the upper end of the piston. To receive and support vehicle

wheels, channeled shaped tracks or guides 13 upon which an automobile is driven, is provided at opposite sides of the body 11.

In order to support and rigidly brace the track or guides 13 a pair of substantially longitudinal bowed I beams 14 is provided. These I beams have intermediate parallel portions 15 embracing the opposite ends of the body 11 and secured thereto by fastenings 16. As illustrated in Figure 2 the extremities of the I beams 14 extend laterally beneath the channeled shaped tracks or guides and are electro-welded or otherwise secured thereto adjacent their ends.

Extending vertically through the hollow piston is a fluid conducting pipe 17 having its lower end threaded in an opening 18 in the closed end 9 of the piston to discharge fluid into the cylinder 5. A fluid return pipe 19 also extends vertically through the hollow piston and has a lateral branch 20 at its upper end extending transversely across a vertical opening 21 in the body 11 and communicating with the inlet of a rotary pump 22 driven by an electric motor 24, the pump motor being supported upon a shelf 25 extending from one of the I beams 14 to the adjacent track 13, and a control switch 26 in circuit with the motor is attached to this track. The supply pipe 17 also has a lateral branch pipe 27 at its upper end extending across the opening 23 and communicates with a check valve 28, the latter in turn having communication with the pump outlet.

To control the passage of fluid to either the cylinder or hollow piston 8, a three way valve 29 is interposed in the branch 27 to the supply pipe 17 between the latter and the check valve 28, and leading therefrom is an outlet pipe 30 which, when the valve is in closed position, directs the fluid into the hollow piston.

An actuating arm 31 is provided with a three way valve, and connected therewith is a longitudinally movable horizontal actuating lever 32 having one end supported in a bracket or guide 33 upon the under face of one of the tracks 13 adjacent the switch 26.

In order to stop the ascent of the piston at a predetermined height a vertical branch

5 pipe 34 having communication with the pipe 19 above its inlet is provided and is arranged with its inlet end above the inlet end of the pipe 19. Normally the lower end of the pipe 34 is sealed by the liquid in the hollow piston permitting the pump to function to lift the liquid therefrom. However, when the liquid recedes below the lower end of the 10 pipe 34 the necessary vacuum in the pipe 19 will be broken preventing further operation of the pump.

Operation

15 With the piston in its extreme lower position as illustrated in Figure 2, the pump being in operation, the valve 29 is opened by manipulation of the handle 4. Vacuum in the pipe 19 reduced by the pump 22 lifts the liquid from the hollow piston directing it under compression into the cylinder 5 by 20 way of the discharge pipe 17 causing ascent of the piston as the cylinder gradually fills. By reason of the inlet in the branch pipe 34 being above the inner end of the pipe 19, the 25 pump will cease to function as above stated when the liquid in the hollow cylinder recedes to a predetermined point, the piston being supported in elevated position to retain its head in elevated position by the column 30 of liquid in the cylinder. To cause the piston to descend the valve 29 is actuated to sever communication between the pump and supply pipe 17 and establish communication between the bleed pipe and discharge pipe. 35 The bleed pipe being open pressure is relieved from the piston allowing it to gravitate forcing the liquid from the cylinder through the discharge pipe and emptying it into the piston by way of the bleed pipe.

40 What is claimed is:—

1. In a vehicle lifting device of the class described, a stationary cylinder, a piston slidable in the cylinder, a body rigidly mounted on the upper end of the piston, 45 means mounted on said body and constructed for accommodating and supporting a vehicle, a motor driven pump on said vehicle supporting means, and valved piping connected with the pump and associated with the piston, 50 ton, said valved piping including a discharge pipe connected through a valve with the pump, a return pipe extending from the valve, the valve being movable to position for affording communication between the discharge pipe and the pump or another position affording communication between the discharge pipe and the return pipe and a supply pipe connected with the pump.

2. In a vehicle lifting device of the class 60 described, a stationary cylinder closed at its bottom, and provided at its top with a stuffing box, a hollow piston slidable in said cylinder, said piston being closed at its bottom, and open at its top, a body having a 65 socket in its under side receiving and closing

the upper end of said piston, vehicle supporting means carried by the body, a motor driven pump carried by said vehicle supporting means, and piping connected with the pump and extending into said piston, said piping including a valve to afford communication between the cylinder and pump or the piston and pump. 70

3. In a structure of the class described, a cylinder, a stuffing box at the upper end of the cylinder, a hollow piston slidable in the cylinder and through said stuffing box, a head supported on the upper end of the piston, a fluid circulating pump on said head, a valved conducting pipe leading from the pump on 80 one side and down through the hollow piston, and communicating at its bottom with said cylinder for delivering fluid into the cylinder to elevate the piston, a return pipe connected with the other side of the pump 85 and extending down into the piston, and terminating in spaced relation to the bottom of said piston, and a branch pipe communicating with the piston and the valved conducting pipe, the lower end of said branch pipe terminating above the lower end of said conducting pipe for causing the pump to cease functioning when the liquid in the piston reaches a predetermined point. 90

4. In a jack structure, a cylinder, a hollow 95 piston therein forming a reservoir, a pump, a discharge pipe between the cylinder and one side of the pump, a valve in said pipe, a return pipe connected with the valve and adapted to discharge into the piston and a supply pipe between a low point in the piston and the other side of said pump. 100
